William O. Michelsen Inventor

Baldwin & Wright

Attornius,

UNITED STATES PATENT OFFICE

WILLIAM O. MICHELSSEN, OF WOODHAVEN, NEW YORK, ASSIGNOR TO ROYAL TYPEWRITER COMPANY, INC., OF NEW YORK, N. Y., A CORPORATION OF NEW YORK

TYPEWRITING MACHINE

Application filed August 17, 1931. Serial No. 557,682.

This invention relates generally to new and useful improvements in manifolding attachments for typewriting machines or the like, although more particularly to the table or guide for the work sheets.

Among the several objects of this invention are to provide a table for guiding a plurality of superposed work sheets forwardly to the platen from a point in rear of the machine frame; to provide laterally adjustable guides for the work sheets whereby work sheets of different widths may be employed; to mount all of the edge guides for independent lateral adjustments whereby one work sheet may be adjustably positioned laterally relative to the other sheet to suit different working conditions, and to provide separate means common to each pair of edge guides for releasably securing the guides in adjusted positions.

With these and other objects in view which will more fully appear, the nature of the invention will be more clearly understood by following the description, the appended claims, and the several views illustrated in the accompanying drawings.

In the accompanying drawings:—

Figure 1 is a perspective view of my invention,

Figure 2 is a top plan view showing the application of the supporting frame of my invention to the carriage of a typewriting machine,

Figure 3 is a vertical sectional view taken on the line 3—3 of Figure 2, but showing the application of the superposed edge guides,

Figure 4 is an enlarged longitudinal sectional view taken through the table,

Figure 5 is a transverse sectional view taken on the line 5—5 of Figure 4,

Figure 6 is a horizontal sectional view taken on the line 6—6 of Figure 5,

Figure 7 is a perspective view of a clamp for a lower guide showing the parts in separated relation, and

Figure 8 is a similar view illustrating a clamp for an upper edge guide.

Referring to the drawings, the typewriting machine includes a main frame A on which

a carriage B is supported for letter space movements. A platen C is fixed to the lower end of a collating frame D which is pivoted to the carriage to swing forwardly and rearwardly upon movement of the carriage return lever E. Type bars F cooperate with the platen, and a main ribbon G is disposed in front of the platen. Work sheets H are led forwardly to the platen over a work guide or table I attached to the carriage from a point in rear of the machine frame, thence over a roller J journaled on the carriage, thence downwardly under a guide roller K journaled on the carriage below the platen, and thence upwardly past the platen and have their upper edge portions clamped to a truck L which is mounted on the collating frame D for line space movements, the truck being line spaced upon movement of the carriage return lever E. A spool supporting frame M is disposed in rear of the machine frame and is attached to the carriage to move therewith, the frame including a rear wall 5 and roller 6 which ride along a rail 7 attached to the main frame A. A plurality of ribbon spools N are rotatably mounted in the spool frame M and the carbon strips or ribbons O are led forwardly along the left side of the carriage, thence along and in front of the platen and in interleaved relation with the work sheets H, and thence rearwardly along the right hand side of the carriage to a ribbon feeding means P which is actuated from the collating frame.

The work table or guide I includes a flat supporting frame formed of sheet metal and comprises spaced side bars 8, 8 which are connected by front and rear cross bars 9 and 10 respectively. The table is disposed above the spool frame M and projects rearwardly therebeyond, the rear wall 5 of the spool frame being riveted to the underface of the front cross bar 9 as shown in Figure 4, to thereby form a central support for the table. Attached to the front ends of the side bars 8, 8 are forwardly extending bracket arms 11, 11 which are detachably connected to the end plates 12, 12 of the carriage by bolts 13, 13. Braces 14, 14 are connected at their upper ends to the rear cross bar 10 and at their

lower ends to the rear plate 5 of the spool frame M.

Mounted on the front cross bar 9 for independent lateral adjustments therealong, are spaced edge guides Q, Q. Each guide which is formed of sheet metal, is of U-shaped cross section, and comprises spaced upper and lower plates 15, 16 and a connecting wall 17. These guides extend in parallelism and in planes at right angles to the cross bar 9, and open inwardly to receive the side edge portions of one of the work sheets H. The cross bar 9 is provided with two longitudinal slots 18, 18 arranged in longitudinal alinement. Normally ineffective clamps 19, 19 are respectively connected rigidly to the guides Q, Q, and are mounted on the cross bar 9 for adjustments along the slots 18, 18. Each clamp comprises a relatively stationary clamping plate 20 having one end portion 20a resting upon the cross bar 9 and overlapping the associated slot 18, and having depending guide ears 21, 21 which project downwardly through the slot. The other end portion 22 of the plate is upwardly offset and rigidly connected to the lower plate 16 of the associated edge guide Q by rivets 23. The guide ears 21, 21 are formed with alined bearing openings 24, 24 for receiving a pivot pin 25. A relatively movable clamping plate 26 is centrally formed with a transverse groove or bearing 27 to receive the pivot pin 25, the plate on one side of the bearing 27 being flat and the other side being curved downwardly out of the plane of the flat side. An operating cam shaft 28 is disposed between the flat sides of the movable clamping plates 26 of both edge guides Q and the under face of the cross bar 9, and has its ends journaled in depending flanges 29, 29 of the side bars 8, 8 of the supporting frame. The shaft is formed with a flat surface 30 which extends substantially throughout its length, and at one end the shaft is provided with a crank arm or handpiece 31. Thus, when the flat surface 30 engages the movable clamping plates 26, 26 as shown in Figure 4, either one or both edge guides Q may be adjusted along the cross bar 9 in either direction and independently of each other. After either one or both edge guides have been adjusted, the cam shaft 28 is turned to cause the peripheral surface of the shaft to simultaneously engage and thereby swing both movable clamping plates 26, 26 about their pivot pins 25, 25, thus causing the end portions 20a of the relatively stationary plates 20 and the curved end portions of the movable or pivoted plates 26 to tightly grip the upper and lower faces of the cross bar 9 to thereby secure the edge guides Q in adjusted position or positions.

The cam shaft 28 is provided with a screw 32 constituting a limiting or stop pin which engages the under face of the cross bar 9 to

limit the turning of the shaft and to retain the shaft in its effective clamping position.

The bracket arms 11, 11 are respectively provided with upstanding arms 33, 33 to which are connected a cross bar 34 provided with longitudinally alined slots 35, 35. Clamps 36, 36 which are substantially identical with the clamps 19, 19 are respectively connected rigidly to upper edge guides R, R, and are mounted on the cross bar 34 for adjustments along the slots 35, 35. Each clamp 36 includes a relatively stationary clamping plate 37 having a pair of ears 38, 38 to which are connected a pivot pin 39, and a relatively movable clamping plate 40 which is constructed like the clamping plate 26 and is pivotally mounted on the pin 39. The edge guides R, R are disposed in superposed relation above the edge guides Q, Q and below the cross bar 34. The relatively stationary clamping plate 37 has slidable contact with the under face of the cross bar 34 and the ears 38, 38 of the clamp project upwardly through the slots 35, 35. The relatively movable or pivoted clamping plate 40 has sliding engagement with the upper surface of the cross bar 34. A cover plate 41 is secured to the cross bar 34 and is provided with depending end flanges 42, 42 which are perforated to form bearings for the ends of a cam shaft 43 which is similar in construction to the cam shaft 28. The cam shaft 43 is provided with a flat surface 44 which extends substantially throughout its length and the shaft is provided at one end with a crank arm or handpiece 45.

From the foregoing, it will be observed that I have provided two pairs of superposed edge guides for the work sheets M, and have mounted these guides in a manner to permit all of them to be independently adjustable laterally whereby different widths of work sheets may be readily accommodated or whereby the lateral position of one work sheet relative to another may be readily obtained, and that I have provided an operating cam shaft for each pair of upper and lower edge guides whereby upon manipulation of the shaft both edge guides will be locked against lateral movement or released to permit of such lateral movement.

I claim:

1. In a typewriting machine, the combination of a work support having a slot, and means for guiding a work sheet along the support comprising an edge guide, a normally ineffective clamp attached to the guide and including a pair of clamping plates respectively disposed above and below the support and including guiding means extending into the slot, and a manually operable cam shaft disposed between and cooperating with the support and with one of said plates for rendering said clamp effective.

2. In a typewriting machine, the combination

nation of a work support having a slot, and means for guiding a work sheet along the support comprising an edge guide disposed above the support, a normally ineffective clamp attached to the guide and including a pair of pivotally connected clamping plates respectively disposed above and below the support, the lower plate being provided with a pair of upstanding guiding ears projecting into the slot, a pivot pin mounted in said ears and having a pivotal connection with the upper plate, and a manually operable cam shaft disposed between and cooperating with the support and with one of said plates for rendering said clamp effective.

3. In a typewriting machine, the combination with a main frame, of a carriage mounted thereon for letter space movements and including a platen, and means for guiding a work sheet to the platen from a point in rear of the main frame comprising a support connected to the carriage to move therewith and provided with alined slots, a pair of edge guides mounted on the support for independent adjustments therewith, a normally ineffective clamp connected to each edge guide and including a pair of pivotally connected clamping plates respectively disposed above and below the support and including guiding means extending into the associated slot, and a single means cooperating with one plate of each clamp to render both clamps effective.

35 4. In a typewriting machine, the combination with a main frame, of a carriage mounted thereon for letter space movements and including a platen, and means for guiding a work sheet to the platen from a point in rear of the main frame comprising a support connected to the carriage to move therewith and provided with alined slots, a pair of edge guides mounted on the support for independent adjustments therewith, a normally ineffective clamp connected to each edge guide and including a pair of pivotally connected clamping plates respectively disposed above and below the support and including guiding means extending into the associated slot, and 50 a manually operable cam shaft extending between and cooperating with the support and with one plate of each clamp to render the clamps effective.

5. In a typewriting machine, the combination of a work support having a slot, and means for guiding a work sheet along the support comprising an edge guide, a normally ineffective clamp attached to the guide and including a pair of clamping plates respectively disposed above and below the support, one of said plates being fixed to the edge guide and provided with a pair of ears extending into the slot, the other plate being pivoted intermediate its ends to said ears, and 65 a manually operable cam journaled on the

support and located between said support and the pivoted plate.

6. In a typewriting machine, the combination of a work support having a slot, and means for guiding a work sheet along the support comprising an edge guide, a normally ineffective clamp attached to the guide and including a pair of clamping plates respectively disposed above and below the support, one of said plates being fixed to the edge guide and provided with a pair of ears extending into the slot, a pivot pin secured to said ears, the other plate being pivoted intermediate its ends to said pin, and a manually operable cam journaled on the support and located between said support and the pivoted plate.

7. In a typewriting machine, the combination of a work support having a slot, and means for guiding a work sheet along the support comprising an edge guide, a normally ineffective clamp attached to the guide and including a pair of clamping plates respectively disposed above and below the support, one of said plates being fixed to the edge guide and provided with a pair of ears extending into the slot, a pivot pin secured to said ears, the other plate being transversely bent to form a bearing engageable with said pin, and a manually operable cam journaled on the support and located between said support and the pivoted plate.

8. In a typewriting machine, the combination with a main frame, of a carriage mounted thereon for letter space movements and including a platen, and means for guiding a work sheet to the platen from a point in rear of the main frame comprising a support connected to the carriage to move therewith, a pair of edge guides mounted on the support for independent adjustments therewith, a normally ineffective clamp connected to each edge guide and movable on the support and including relatively stationary and movable clamping plates disposed above and below the support for cooperation therewith, one of said plates being fixed to the edge guide and provided with a pair of ears extending into the slot, the other plate being pivoted intermediate its ends to said ears, and a manually operable cam shaft journaled on the support and located between the support and the pivoted plates of both clamps.

In testimony whereof, I have hereunto subscribed my name.

WILLIAM O. MICHELSEN.
